AUTOTRANSFORMER**Ezra C. Hill, Fort Wayne, Ind., assignor to General Electric Company, a corporation of New York****Application March 2, 1954, Serial No. 413,571****4 Claims. (Cl. 336—220)**

This invention relates to electrical transformers and more particularly to high voltage impulse transformers.

High voltage impulse transformers are used in many applications, for example, in capacitor discharge systems for operating stroboscopic flash equipment for photography. Such transformers conventionally comprise a primary winding, usually having a single layer of relatively large wire wound over a core, and a secondary winding usually having a number of layers of relatively fine wire wound over the primary winding. These transformers are frequently auto-transformer connected and thus when the secondary winding is wound over the primary, it is necessary to bring out the inner or starting end of the secondary winding in order to connect it to one end of the primary winding. Since these transformers are relatively small in size, it has been difficult to pull out the inner end of the fine wire secondary winding thus resulting in the damaging of an unduly large number of coils in the effort to make this connection.

It has been found that if the inner or starting end of the fine wire secondary winding is left unconnected, the voltage induced in the secondary winding breaks through the insulation separating the two windings to complete the autotransformer circuit. In an impulse transformer application, such as in connection with a flash tube, the energy level in the arc formed between the two windings is sufficiently low that the insulation is not injured thereby and the elimination of the requirement of bringing out the inner end of the secondary winding and connecting it to the primary winding has effected a marked reduction in the overall cost of the device. Further, the elimination of this connection is not only effected without any detriment to the performance of the device, but in fact results in a slight gain in performance.

It is, therefore, an object of this invention to provide an improved autotransformer wherein one end of the secondary winding is not connected to the primary winding.

Further objects and advantages of this invention will become apparent and the invention will be better understood by reference to the following description and the accompanying drawing, and the features of novelty which characterize this invention will be pointed out with particularity in the claims annexed to and forming a part of this specification.

This invention in its broadest aspects provides an autotransformer having a primary winding with its two ends being adapted to be connected to a source of pulsating voltage. A secondary winding is provided adjacent the primary winding and electrical leads are provided for connecting one end of the secondary winding and one end of the primary winding across the load. The other end of the secondary winding is left free so that the voltage induced therein breaks through the insulation separating the windings to complete the autotransformer circuit.

In the drawing:

Fig. 1 is a schematic illustration showing the application of the improved autotransformer of this invention in connection with a flash tube; and

2

Fig. 2 is a view in perspective, partly broken away, showing the improved autotransformer construction of this invention.

Referring now to Fig. 1, the improved autotransformer 5 of this invention is schematically shown at 1 and comprises a core 2 with a primary winding 3 and secondary winding 4 arranged thereon. Primary winding 3 has its ends 5 and 6 respectively connected to one terminal of triggering capacitor 7 and to grounded common bus 8. 10 The other terminal of capacitor 7 is connected to the mid-point 9 between series resistors 10 and 11 which are connected across positive line 12 and common bus 8. A switch 13 is connected across resistor 11 and its function will be hereinafter described. A main storage capacitor 14 is connected across lines 12 and 8 which in turn are adapted to be connected to an external source of direct current (not shown). A photoflash tube 15 is provided having its cathode 16 connected to grounded bus 8 and its anode 17 connected to positive line 12. The triggering electrode 18 of photoflash tube 15 is connected to one end 19 of secondary winding 4 and the other end 20, which normally would be connected to end 5 of primary winding 3 in order to complete an autotransformer circuit, is left free as shown.

25 In operation, with lines 8 and 12 connected to a source of direct current, storage capacitor 14 is charged as is triggering capacitor 7. When switch 13 is closed, triggering capacitor 7 is discharged through primary winding 3 of transformer 1 and since the loop circuit formed by 30 the switch 13, capacitor 7, primary winding 3 and common line 8 is an LC circuit, an oscillatory discharge will result. This oscillatory discharge through primary winding 3 induces a voltage in secondary winding 4. Secondary winding 4 is preferably constructed with many 35 more turns than primary winding 3 so that the induced open circuit peak voltage across primary winding 4 is sufficient to break down the insulation between primary winding 3 and secondary winding 4. An arc is thus formed between end 20 of secondary winding 4 and primary winding 3 completing an autotransformer connection and placing the combined voltages of primary winding 3 in secondary winding 4 across cathode 16 and triggering electrode 18 of photoflash tube 15. This voltage is sufficient to ionize the tube and will cause main energy 40 capacitor 14 to discharge across anode 17 and cathode 16 of photoflash tube 15. While the improved autotransformer 1 is shown in connection with a capacitor discharge system for a photoflash tube, it will be readily understood that this is by way of illustration only and that 45 the improved autotransformer 1 may be used in other 50 applications.

Referring now to Fig. 2, there is shown a preferred embodiment of this invention in which the autotransformer 1 comprises a cylindrical core 2 formed of magnetic material, such as sintered material. The primary winding 3, preferably comprising a single layer of relatively heavy wire is wound over a spool 19 formed of insulating material and its ends 5 and 6 are left exposed. The starting end 20 of the secondary winding 4, which 55 is preferably formed of relatively fine wire is mechanically but not electrically connected to the outer surface of the primary winding 3, as by suitable adhesive tape 21. A layer insulator 22 is then inserted between the end 20 of secondary winding 4 and primary winding 3 and the first 60 layer of the secondary winding 4 is then wound. It will be seen that the outer edge 23 of the insulator 22 overlaps the inner edge 24 so that only the end 20 of secondary winding 4 extends between the two edges to a position adjacent the primary winding 3. The secondary winding 65 4 is preferably formed of a plurality of layers of fine wire with layer insulators 25 separating each layer. It will thus be seen that the outer or finishing end 19 of second-

ary winding 4 is on the outer periphery of the coil and comes out under the outer edge 27 of the outer layer insulation 25. In order to prevent arcing over between the secondary winding 4 and primary winding 3 at any point except between end 20 and the adjacent turn of primary winding 3, secondary winding 4 is axially shorter than primary winding 3 and its axial ends 23 and 29 are spaced from the axial ends of primary winding 3. Layer insulation 22 and 25 on the other hand is substantially the same length as primary winding 3 and thus extends substantially beyond the axial ends 23 and 29 of secondary winding 4.

In a transformer actually constructed in accordance with this invention, the primary winding 3 consisted of 46 turns of .0126" diameter wire wound over a spool 26 having a $\frac{1}{4}$ " diameter. The secondary winding 4 consisted of 1850 turns of .0031" diameter wire in several layers. This transformer was connected in a circuit shown in Fig. 1 and the primary winding 3 was energized by discharge of a $\frac{1}{4}$ microfarad capacitor charged to 160 volts. This produced a 5000 peak voltage across secondary winding 4. This high voltage pulse was sufficient to break through the insulation on the fine wire of secondary 4 and the insulation on the wire of primary winding 3, the arc being formed between end 20 of secondary winding 4 and the adjacent turn of primary winding 3. The energy level in this arc was sufficiently low and the duration sufficiently short to prevent injury to the transformer.

It will be readily seen that this improved construction eliminates the necessity for bringing out the end 20 of secondary winding 4 after the coil has been wound and for connecting this end to the primary winding. This eliminates the cost of making the connection and further eliminates the numerous rejected coils which were damaged in the course of making this connection. While the transformer of Fig. 2 has been shown with the secondary winding 4 wound over the primary winding 3, it will be readily understood that the primary winding may be wound over the secondary winding or that a different core construction may be used with the secondary winding being arranged adjacent the primary winding. With the end 20 of secondary winding 4 being unconnected, no voltage appears across lines 19 and 8 until the arc has been formed between end 20 and primary winding 3. This provides a very peaked, steep wave front and it is well known that photoflash tubes are more sensitive to higher frequencies, i. e. to steep wave fronts. It is thus seen that the improved transformer 1 is not detrimental to the performance of flash tube 15, but on the contrary provides slightly improved performance.

While I have shown and described a particular embodiment of this invention, further modifications and improvements will occur to those skilled in the art. I desire that it be understood therefore that this invention is not limited to the particular form shown and I intend in the appended claims to cover all modifications which do not depart from the spirit and scope of this invention.

What I claim as new and desire to secure by Letters Patent of the United States is:

1. An autotransformer comprising a cylindrical core, a primary winding having a single layer of wire wound on said core, a sheet of insulation material surrounding said primary winding and having one axial edge overlapping its other axial edge, a secondary winding having a plurality of layers of wire wound over said insulation and having one end positioned under said overlapping edge of said insulation and secured adjacent and electrically insulated from said primary winding adjacent one end thereof, said sheet being of a quality to insulate said windings from each other during operation of said autotransformer, the insulation between said primary winding and said one end of said secondary winding being of a quality to permit arcing therebetween during opera-

tion of said autotransformer, said secondary winding being axially shorter than said primary winding and its axial edges being respectively spaced from the axial edges of said primary winding, insulation separating each of said secondary winding layers, said insulation having substantially the same axial length as said primary winding, and electrical leads connected to the other end of said primary winding and the other end of said secondary winding respectively whereby said windings may be connected across a load.

2. An autotransformer comprising a core, a primary winding wound on said core, a secondary winding having a plurality of layers of wire wound over said primary winding with the starting end adjacent said primary winding and the finishing end on the outer periphery of said secondary winding, insulating material spacing said secondary winding from said primary winding and of a quality to insulate said windings from each other during operation of said autotransformer, said starting end of said secondary winding extending inwardly past said insulating material and being secured adjacent and electrically insulated from said primary winding adjacent an end thereof, the insulation between said primary winding and said secondary winding starting end being of a quality to permit arcing therebetween during operation of said autotransformer, said secondary winding being axially shorter than said primary winding and its axial edges being respectively spaced from the axial edges of said primary winding, insulation separating each of said secondary winding layers, and electrical leads connected respectively to the other end of said primary winding and to said finishing end of said secondary winding whereby said windings may be connected across a load.

3. An autotransformer comprising a core, a primary winding wound on said core, a sheet of insulation material surrounding said primary winding and having one axial edge over-lapping its other edge, a secondary winding having a plurality of layers of wire wound over said insulation and having one end positioned under said over-lapping edge of said insulation and secured adjacent and electrically insulated from said primary winding adjacent an end thereof, said sheet being of a quality to insulate said windings from each other during operation of said autotransformer, the insulation between said primary winding and said one end of said secondary winding being of a quality to permit arcing therebetween during operation of said autotransformer, said secondary winding being axially shorter than said primary winding and its axial edges being respectively spaced from the axial edges of said primary winding, insulation separating each of said secondary winding layers, and electrical leads connected respectively to the other end of said primary winding and the other end of said secondary winding whereby said windings may be connected across a load.

4. An autotransformer comprising a core, a primary winding having a single layer of wire wound on said core, a secondary winding having a plurality of layers of wire wound over said primary winding with the starting end adjacent said primary winding and the finishing end on the outer periphery of said secondary winding, insulating material spacing said secondary winding from said primary winding and of a quality to insulate said windings from each other during operation of said autotransformer, said starting end of said secondary winding extending inwardly past said insulating material and being secured adjacent and electrically insulated from said primary winding adjacent an end thereof, the insulation between said primary winding and said secondary winding starting and being of a quality to permit arcing therebetween during operation of said autotransformer, said secondary winding being axially shorter than said primary winding and its axial edges being respectively spaced from the axial edges of said primary winding, insulation separating each of said secondary winding layers, said insulation having substantially the same axial length

as said primary winding, and electrical leads connected respectively to the other end of said primary winding and to said finishing end of said secondary winding whereby said windings may be connected across a load.
